G. E. COLMAN.
BOWLING ALLEY,
APPLICATION FILED NOV. 9, 1916.

1,245,684.

Patented Nov. 6, 1917.

*Inventor:
George E. Colman,
by Walter E. Lombard
Atty.*

UNITED STATES PATENT OFFICE.

GEORGE E. COLMAN, OF BOSTON, MASSACHUSETTS.

BOWLING-ALLEY.

1,245,684.

Specification of Letters Patent.

Patented Nov. 6, 1917.

Application filed November 9, 1916. Serial No. 130,460.

To all whom it may concern:

Be it known that I, GEORGE E. COLMAN, a citizen of the United States of America, and a resident of Boston, in the county of 5 Suffolk and Commonwealth of Massachusetts, have invented certain new and useful Improvements in Bowling-Alleys, of which the following is a specification.

This invention relates to toy bowling 10 alleys adapted to be used as a parlor game, and it has for its object the production of a device of this character which may be folded into a small space when not in use.

Another object of the invention is to provide 15 a ball track therefor, the inclination of which may be varied at will to give a greater or lesser momentum to the balls as desired.

A further object of the invention is to 20 provide a simple arrangement for the return of the spent balls to a point within the reach of the player.

The invention consists in certain novel 25 features of construction and arrangement of parts which will be fully understood by reference to the description of the drawings and to the claims hereinafter given.

For the purpose of illustrating the invention one preferred form thereof is illustrated 30 in the drawings, this form having been found to give satisfactory and reliable results, although it is to be understood that the various instrumentalities of which the invention consists can be variously arranged 35 and organized, and that the invention is not limited to the precise arrangement and organization of these instrumentalities as herein shown and described.

Of the drawings:

40 Figure 1 represents a plan of a bowling alley embodying the principles of the present invention.

Fig. 2 represents a longitudinal vertical section of the same, on line 2—2 on Fig. 1.

45 Fig. 3 represents a horizontal section on line 3—3 on Fig. 2.

Fig. 4 represents a transverse vertical section on line 4—4 on Fig. 2.

Fig. 5 represents a section on line 2—2, 50 showing the parts folded together when not in use, and

Figs. 6 and 7 represent details of a modified form of ball track.

Similar characters designate like parts 55 throughout the several figures of the drawings.

In the drawings, 10 is a pin table having side walls 11 and an end wall 12 extending upwardly above said table. Between the side walls 11 and the table 10 are gutters 60 12^x. The rear end of the table 10 is separated from the end wall 12, permitting the balls to fall upon the inclined bottom 13.

The bottom 13 inclines downwardly toward the front of the table 10, and is provided on its upper surface with a diagonal cleat 14 which is adapted to direct the spent balls on the inclined bottom 13 to an opening 15 in a transom 16 extending transversely beneath the table 10 and between 70 the walls 11. In front of the transom 16 is a trough 17 adapted to receive the spent balls.

To the front ends of the side walls 11 are pivoted at 18 the side walls 19 of a ball 75 track 20. To the front ends and inner faces of the side walls 19 are pivoted at 21 the supports 22.

The ball track 20 at its front end is provided with two slots 23 between the inner 80 faces of the side walls 19, said slots being adapted to receive the supports 22 when the apparatus is in use. It is obvious that the supports 22 may be practically as indicated in the drawings, or at any desired inclination, thereby varying the inclination of the ball track 20, and thus varying the speed of the balls as they pass down the inclined track 20 onto the horizontal pin table 10. When the apparatus is not in use the supports 22 are folded over the inside of the side walls 19, and the ball track is then folded over upon the table 10, said side walls 19 and supports 22 being partially positioned within the gutters 12^x, all as shown 90 95 in Fig. 5 of the drawings.

The pins 23^x have secured to their lower ends cords 24 extending through vertical openings in the table 10, said cords 24 all being connected at 25 to a single cord 26 100 extending through a staple 27 on the under side of the table 10, and being connected at its outer end 28 to the front end of the ball track 20.

When the pins 23^x have been upset they 105 may again be set in position by pulling upon the cord 26. When the apparatus is not in use the pins 23^x may lie flat upon the table 10 in the position indicated in Fig. 5 of the drawings.

The trough 17 is in such position that the operator may readily remove the balls there-

from when playing the game. Extending transversely of the apparatus between the side walls 11 are two wires 29 which support the cords 24 and 26 and prevent them 5 from sagging down into the path of the balls as they move down the inclined bottom 13. If desired, the inclined ball track 20 as shown in Figs. 1 to 5 of the drawings may be dispensed with and a modified form 10 of track used such as is shown in Figs. 6 and 7 of the drawings. This modified form consists of a rod 30 extending transversely of the front end of the apparatus between the side walls 11. Loosely pivoted to the 15 rod 30 by means of eyes 31 surrounding said rod are two parallel rods 32 the outer ends of which are secured in a handle 33. When this modified form of ball track is used the operator seizes with his left hand the handle 20 33 and moves it into any desired vertical inclination or at any desired horizontal angle to the rod 30 and places the ball on the rods 32 adjacent to the handle 33 and permits said balls to run down the track formed 25 by said rods 32 onto the table 10.

By means of this toy device a game of ten pins may be played in practically the same manner that the game is played upon a full-sized bowling alley. When not in 30 use the device may be folded up in small compass, as indicated in Fig. 5.

It is believed that the operation and many advantages of this device will be fully understood from the foregoing description.

35 Having thus described my invention, I claim:

1. In a bowling alley, a pin table; side walls therefor extending above the upper surface and beyond the rear end thereof; an end 40 wall removed from the rear end of said table and connected to said side walls; a bottom secured to said side walls and inclining downwardly from said rear wall to the front of said table; a transom interposed

between and secured to the opposite side 45 walls beneath the front end of said table, said transom being positioned at the front end of said inclined bottom and having a delivery opening therein; and a cleat diagonally secured to the upper face of said 50 bottom with its rear end abutting a side wall and adapted to direct the spent balls to said delivery opening.

2. In a bowling alley, a pin table; side walls therefor extending above the upper surface 55 and beyond the rear end thereof; an end wall removed from the rear end of said table and connected to said side walls; a bottom secured to said side walls and inclining downwardly from said rear wall to the 60 front of said table; a transom interposed between and secured to the opposite side walls beneath the front end of said table, said transom being positioned at the front end of the inclined bottom and having a 65 delivery opening therein; a cleat diagonally secured to the upper face of said bottom with its rear end abutting a side wall and adapted to direct the spent balls to said delivery opening; and a ball trough beneath 70 the front end of said table and communicating with said delivery opening.

3. In a bowling alley, a pin table having gutters on opposite sides thereof; side walls outside of said gutters; a ball track with 75 side walls pivoted to the front ends of the side walls of said table and adapted to be folded over into said gutters; and supports pivoted to the front end of said ball track and adapted to be folded over within the 80 walls of said track.

Signed by me at 4 Post Office Sq., Boston, Mass., this 8th day of November, 1916.

GEORGE E. COLMAN.
